UNITED STATES PATENT OFFICE.

JAMES HARVEY MORLAN, OF LEBO, KANSAS.

CLOTHES-DRIER.

SPECIFICATION forming part of Letters Patent No. 339,678, dated April 13, 1886.

Application filed October 20, 1885. Serial No. 180,412. (Model.)

To all whom it may concern:

Be it known that I, JAMES HARVEY MORLAN, a citizen of the United States, residing at Lebo, in the county of Coffey and State of Kansas, have invented certain new and useful Improvements in Clothes-Driers, of which the following is a specification, reference being had therein to the accompanying drawings.

10 This invention relates to improvements in clothes-driers, and has for its objects to furnish a compact device for this purpose, which may be easily taken apart or folded up, so as to occupy small space when not in use. It 15 will be seen that it is at once simple, durable, cheap, and handy. These objects are attained by the devices illustrated in the accompanying drawings, forming a part of this specification, in which—

20 Figure 1 is an elevation. Fig. 2 is a plan view.

The letter A indicates the lower portion, forming a bench or stool having three legs, a, spread out, so as to insure its standing firmly 25 and prevent its being easily turned over. The legs a are secured to a circular piece of board, A', by means of screws, or in any other convenient manner. This board has a central opening for the passage of the lower part, b, 30 of the post B, which is of a circular cross-section, for a purpose hereinafter mentioned. A little above the circular piece of board A' is another piece of the same shape, A, also having a central opening for the same purpose as 35 the central opening in the piece A'. The legs a enter the lower part of the piece A, and are securely fastened therein, thus forming a bench or stool, which may be detached from the upper part of the drier. Just above the circular piece A is another piece, A'', provided 40 with a central opening for the passage of the post b. The piece A'' is provided with staples C on its opposite sides, which are intended to engage with hooks D, attached to the lower piece, A', and thereby fasten these parts to each other. A snap-bolt, E, provided with a spring, e, passes through the piece A'', and enters a groove in the post b, at each end of which is a cavity or hole, G, into which the 45 point of the bolt E may enter, for the purpose of holding the piece A'' in the proper position when the arms of the drier are extended or lowered, as the case may be. On the upper side of the piece A'' are pivoted eight sup-

porting-rods, I, which extend in an upward 55 direction and have their upper ends secured to eight arms, K K', extending radially from the post B, to which they are hinged or pivoted, preferably by having their inner ends enter the mortises H H', and secured therein 6c by the bolts or pivots h h'.

On the upper end of the post B is a ring, J, which is intended to provide a convenient means of lifting the clothes rack or drier from the stool, when it is desired to separate the 65 two.

The radial arms K K' have galvanized-wire links or chains L secured thereto, upon which to hang the clothes to be dried, and give on a full-sized rack seventy-five feet and upward 70 of line. A full-sized rack will be five feet high and six feet across.

The lower part, b, of the post B is made round, in order to be turned on its axis, which enables the person to put on or take off the clothes 75 without moving from one place to another.

In order to permit the rack to be turned on its axis, the hooks must be unhooked.

Having described my invention, what I desire to secure by Letters Patent and claim, 80 is—

1. In a clothes-drier, the post B, having a handle, J, and slots H H', and radial arms K K', pivoted therein, provided with links L and supporting-rods I, in combination with 85 the circular piece A'', having a central opening for the passage of the lower part of the said post B, and the circular piece A, having legs a, secured to the periphery of a lower circular piece, A', as shown and described, and for 90 the purposes set forth.

2. In a clothes-drier, the post B, having radial arms K K', provided with links L and supporting-rods I, secured to a circular piece of board, A'', having a central opening for 95 the passage of the part b of said post B, in combination with a supporting-stool consisting of circular pieces of board A A', provided with legs a, the said piece A' having hooks D, whereby the upper part of the drier may 100 be attached to said stool, as described, and for the purposes set forth.

In testimony whereof I affix my signature in presence of two witnesses.

JAMES HARVEY MORLAN.
